UNITED STATES PATENT OFFICE.

ALMONT A. BAILEY, JR., OF PORTLAND, OREGON.

LINOTYPE-MOLD.

1,091,724.

Specification of Letters Patent. Patented Mar. 31, 1914.

Application filed July 17, 1912. Serial No. 709,854.

To all whom it may concern:

Be it known that I, ALMONT A. BAILEY, Jr., a citizen of the United States, residing in the city of Portland, county of Multnomah, and State of Oregon, have invented 5 certain new and useful Improvements in Linotype-Molds, of which the following is a specification.

My invention relates to linotype molds, 10 and more particularly to improvements therein whereby I am able to do away absolutely with the use of "liners", now used in molds for making the different sizes and different lengths of type lines, or linotype 15 "slugs", as they are commonly designated.

In many machines the longest line which 20 can be set up on a linotype at present is thirty picas (printer's measure), and the shortest line or slug which can be cast and 25 ejected from the mold, without a great deal of trouble, is five picas. From five picas to thirty picas there are twenty-five picas, making it possible to cast twenty-five different lengths of slugs. If half picas be used, then 30 fifty different lengths of type lines or slugs can be made in a mold. The most common thickness of these slugs as used in linotype machines is from five points (12 points, standard, being 1 pica) up to and including 35 fourteen points, the $5\frac{1}{2}$ point type (agate) being the only size with a fraction. We have, therefore, from 5 points to 14 points, or eleven different thicknesses of slugs, viz. 40 $5, 5\frac{1}{2}, 6, 7, 8, 9, 10, 11, 12, 13$ and 14 points.

By my invention I have produced a universal mold by means of which and without the use of any liners or similar pieces, I am able to quickly and conveniently 45 change the mold for type lines or slugs of any of the lengths or thicknesses within the capacity of the mold, that is, for example, for eleven different sizes or thicknesses of slugs with fifty different lengths for each size.

In order that others may understand my invention, I have shown in the accompanying sheet of drawings one practical embodiment thereof which I will now describe.

In the drawings Figure 1 is a face or 50 side elevation of a mold, partly in section, with my invention embodied therein, and taken on line 1-1 of Fig. 2. Fig. 2 is an end view of the same; Fig. 3 is a top plan view thereof; Fig. 4 is a cross sectional view 55 taken on line 4-4, Fig. 1; Fig. 5 is an enlarged right end view, with a part broken

away; Fig. 6 is an enlarged left end view, with a part broken away; Fig. 7 shows side and edge views, with parts broken away, of a lock and guide bar; Fig. 8 is a flat view of a linotype slug with part broken out to shorten the figure; and Fig. 9 is a detail view showing a slight modification with guide and scale members in section.

Referring now to the drawings illustrating one embodiment of the invention, 60 1 designates the body of a mold which is inserted into the disk (not shown) of a linotype machine in the usual manner. Mounted in the mold and as a part thereof is a series 65 of segments 2, there being shown twenty-five of these segments of a uniform size, each corresponding in thickness to a pica, with a block or segment 3 at the right end shown to be equal to five picas in length, and with 70 a clamping block 4 at the left end, slidably mounted upon the mold by an interfitting or dovetailed connection therewith, as indicated in Fig. 6. I will refer to the segments 75 2 as pica segments, although it is to be 80 understood that these segments may be and some times are each made in thickness to correspond to a half-pica.

Each pica segment is shown provided at 85 one side with an off-set portion, forming a lip, as 5, to the right, and a groove, as 6, at the left thereof. The five pica segment 3 is provided with a groove at each corner of its rear side, and the clamping block 4 is provided with a lip 5, as is also the upper 90 portion of the mold 1 at the right end thereof. The object of these lips at the rear sides of the segments is to form or mold the type line or slug with their corners cut out, as indicated at A, Fig. 8. This will be understood from the top plan view in Fig. 3. Each of said segments is provided with an angular opening, as 7, therein, adapted to 95 receive a combination lock and guide member 8, shown in side and edge views in Figs. 100 7, said openings 7 being long enough to permit of vertical adjustment of the pica segments to provide different thicknesses of molding spaces. The member 8 is provided 105 at its right end with a head, as 9, which is countersunk into the end of the mold 1, in the manner indicated in dotted lines, Fig. 3, and at its opposite end, it is reduced in size and threaded, as at 10, and passes through the clamping block 4 to receive a screw cap 110 11, which said cap 11 is also countersunk into block 4, and is adapted to rest against

a shoulder (12), indicated in dotted lines in said clamping block 4, thereby making it possible, by tightening said screw cap 11, to draw and clamp or lock said pica segments 2, 3 and block 4 together and to hold them against movement.

In order to provide the proper molding space in said mold in which to form the slug, it is only necessary to move the right 10 number of segments the right distance and lock them in the adjusted position. This may be done in a variety of ways. I have shown two practical ways. I provide the segments with openings, as 13, which are in 15 register with each other when the segments are in place. The openings are shown square and are adapted to receive an operating or spacing member 14, said member being shown to be of rectangular form in cross 20 section and is adapted to be inserted through a cylindrical member 15, in the end of the mold 1, and thence to any desired distance through the segment 3 and the pica segments 2 whereby said separate segments can 25 be moved in series. To this end, said member is graduated, as indicated in Fig. 1, whereby it is easy to accurately determine how far into said mold, or through how 30 inserted in order to get the desired length of molding space for the slug to be formed therein. The cylinder 15 is rotatably mounted in the end of the mold 1 and is provided upon its inner end with a head or 35 flange to prevent its accidental removal from the mold. It is necessary, therefore, in assembling the parts, to insert the cylinder 15 from the inside and then to place the segment block 3 and the pica segments 2 40 afterward. The operating or spacing member 14 is provided with graduation marks extending longitudinally thereof, in order to determine accurately the distance into the mold and the segments it is necessary 45 to insert said spacing member in order to provide for the proper or desired length of line. In order to accurately determine the thickness of said type line or slug, which is accomplished by the movement of the seg- 50 ments away from the body of the mold 1, I have provided upon the end of the mold, adjacent and circumferentially of the end of the cylinder 15 a series of graduations from 0 to 12, each mark being equal to one point, 55 and have placed upon the end of the cylinder 15 an arrow, as indicated. The opening through the cylinder 15 is of the same form as the operating or spacing member 14 in cross section, so that when the mem- 60 ber 14 is inserted through said cylinder 15 and through any number of the segments, the cylinder must turn with the operating or spacing member. It will, therefore, be seen that the distance to which said spac- 65 ing member is inserted into the mold and

segments, as indicated upon the graduations upon said member, determines the length of the type line or slug, and the amount said member is turned circumferentially determines the thickness of said slug, the turning of the spacing member 14 operating to move the segments through which it is inserted to any desired number of points within the capacity of the mold. If, for example, the member 14 is inserted to the mark 70 24 of its graduation, as it is shown in Fig. 1, and is turned to the position indicated by the arrow in Fig. 2 to point 6, the right number of pica segments will be raised to provide space for a type line or slug 75 24 picas in length, and said segments will be raised or moved to provide a space for a slug six points in thickness. When the segments have been moved thus, as desired, the screw cap 11 is tightened upon the end of the lock and guide member 8 so as to bind or clamp said segments firmly in the adjusted position, after which the operating or spacing member is removed from the mold.

It will thus be understood that my invention, broadly considered, contemplates a linotype mold composed in part of segments, which segments are adapted to be moved to different positions relative to the body proper of the mold in order to provide a 90 molding space for the slug to be formed, and that the number of segments moved, and the distance to which they are moved, determine, respectively, the length of the type line or slug and the thickness thereof. 95

I am aware that changes and modifications can be made in the embodiment of the invention here shown for purposes of illustration without departing from the spirit thereof, and I do not limit the invention to the particular embodiment here shown, except as I may be limited by the hereto appended claims, for various ways can be devised for selecting and moving the segments and I have shown in Fig. 9 a pica segment 2' provided with a rack, as 16, and a segment operating or spacing shaft or member 17, instead of a cam member, for raising the segments to determine the thickness of the slug. 100

The methods I have shown and described for selecting and moving the desired number of segments are the preferred ways of accomplishing the desired result.

I claim:

1. In combination with a mold body for linotype machine, a series of segments with openings therethrough mounted together side by side therein to form a portion of said mold, said segments being adapted to be moved in groups relative to the mold body to provide a molding space, and a locking device extending through said segments for locking said segments in adjusted positions. 125

2. In a linotype mold, a body, a series of 130

- segments movably mounted therein and forming a part of said mold, a spacing member adapted to be inserted into said mold whereby to move some or all of said segments away from the body of the mold to different distances to provide molding spaces of different thicknesses, and means for locking said segments in adjusted positions.
3. In a linotype mold, the combination with the body of said mold, of a series of pica segments forming a part thereof, said segments being adapted to be moved relative to said body whereby to provide molding space, a graduated spacing member adapted to be inserted into said mold for moving said segments in groups, and means for locking said segments in adjusted positions.
4. In combination with a linotype mold, a series of pica segments movably mounted therein, a graduated spacing member adapted to be inserted into said mold longitudinally thereof whereby to have operative engagement with said segments, said spacing member being adapted to be turned to move said segments relative to said mold body, and means for locking said segments in various positions of adjustment.
5. In a linotype machine, a mold having a series of segments forming a part thereof and adapted to be moved into different positions whereby to open molding spaces of different dimensions, and a spacing member provided with graduation marks longitudinally thereof and adapted to be inserted into said mold and into operative connection with some or all of said segments, whereby to engage and move said segments to different positions.
6. In a linotype machine, a mold having a series of segments forming a part thereof and adapted to be moved into different positions whereby to open molding spaces of different dimensions, a spacing member provided with graduations longitudinally thereof and adapted to be rotatably inserted into said mold and into operative connection with some or all of said segments, said mold being provided with graduation marks arranged circumferentially of said spacing member, whereby the turning of said member upon its longitudinal axis within said mold, operates to move said segments relative to the mold body according to said graduation marks, and means for locking said segments in adjusted position.
7. A linotype mold comprising in combination a body portion, a series of segments movably mounted therein, a lock and guide bar mounted through said body and said segments to permit the movement of the latter, a spacing member movably mounted through said body and said segments and adapted to have rotative operative connections with said segments, whereby to positively move the latter to different positions relative to the body of the mold, and means whereby to determine the particular segments to be moved.
8. In a linotype mold, a body, a series of segments adjustably mounted side by side therein and movable in series to form molding spaces, said segments being provided with projecting lips, whereby to form the linotype slugs with corners as indicated.
9. In a linotype mold, in combination with the body thereof, a series of pica segments, a clamping block, a combination guide and lock bar through said mold, segments and clamping block and adapted to lock said parts in different positions of adjustment, said parts being adapted to receive a spacing member and provided with graduation marks whereby to determine the movement of said parts and the size of the molding space.
10. In a linotype mold, in combination with the body thereof, of a series of small segments arranged side by side and forming a part of said body, said segments being provided with openings therethrough and in alignment with each other, and a spacing element adapted to be inserted through said openings and to be rotated to move the segments through which it passes into different positions of adjustment.
11. A linotype mold comprising a mold body having one side thereof formed of a series of segments arranged side by side lengthwise of said body, said segments being movable away from the body in series to different distances, whereby to provide molding spaces of different thicknesses between the body and the moved segments, and a spacing member adapted to be revolvably moved within said body and segments for moving the latter away from said body, for the purpose referred to.

Signed at Portland, Oregon, this 6th day of July, 1912.
